UNITED STATES PATENT OFFICE.

HARRY ASHTON REED, OF NEW YORK, N. Y., ASSIGNOR TO CARBONIC CONDENSING CO., OF HOBOKEN, NEW JERSEY, A CORPORATION OF NEW JERSEY.

PRESSURE-REDUCER FOR GASEOUS LIQUIDS.

No. 901,741.

Specification of Letters Patent.

Patented Oct. 20, 1908.

Application filed August 19, 1907. Serial No. 389,281.

To all whom it may concern:

Be it known that I, HARRY ASHTON REED, a citizen of the United States, and a resident of the city of New York, borough of Manhattan, in the county and State of New York, have invented new and useful Improvements in Pressure-Reducers for Gaseous Liquids, of which the following is a full, clear, and exact description.

10 This invention is an improvement in pressure reducers for ale, beer and other gaseous liquids, having for an object primarily to reduce the pressure of the fluid in drawing it from the barrel or cask, whereby the gas and liquid will pass out in proper proportions without waste of the gas, and thus obviate the danger of the beverage becoming flat.

15 The invention further resides in certain special features of construction and arrangement of parts which will be fully set forth hereinafter and particularly pointed out in the claims.

20 Reference is to be had to the accompanying drawings forming a part of this specification, in which similar characters of reference indicate corresponding parts in all the views.

25 Figure 1 is a side elevation of the invention complete, partly shown in central vertical section; Fig. 2 is a cross section through the 30 connection between the storage, cooling and settling tank and a three-way valve arranged in the length of the liquid supply; and Fig. 3 is a central vertical section through the pressure reducing valve.

35 The invention is composed of a tank 5 of copper or other suitable material for storing, cooling and settling the liquid, and is connected at its bottom with a supply pipe or passage 6 which leads from the source of 40 supply, which is ordinarily one or more casks of beer, ale or other gaseous liquid, located in the cellar or basement, together with my improved pressure reducing appliance, the latter being contained in an ice box or other 45 cool place.

The supply pipe or passage is provided at a point in its length with a strainer 7, and at a point therebeyond with a pressure reducing valve 8, as also with pressure gages 9 and 50 10 located respectively at each side of the reducing valve.

Adjacent to the tank 5, the passage 6 leads through a three-way valve 11 which is preferably directly secured to the tank, as illus-

trated in Fig. 2, by means of a collar 12. 55 The said collar is counterbored on its under face to receive a counterpart shoulder formed on the valve flange and operating when the collar is tightened to press into the base of the tank and form a liquid and gas- 60 tight joint.

The three-way valve 11 provides communication between the passage and tank or between the tank and a cock 13 located at one side thereof.

65 Leading from the top of the tank to the point at which the beer or ale is drawn is a vent-pipe 14 and a discharge-pipe or passage 15, the latter passing from a point near the bottom of the tank and is jointly connected 70 at the top of the tank by a suitable coupling 16. The discharge-pipe 15 has a hand-operated valve 17 arranged slightly above the tank, and is also connected at a point therebeyond with a by-pass 18 which leads from 75 the supply pipe 6 intermediate the reducing valve 8 and pressure gage 9, the connection at this point being effected through a three-way valve 19 which permits of the liquid supply being taken directly from the cask 80 without reduction of pressure as should the pressure reducing mechanism become deranged, or for other reasons. The by-pass 18 can also be cut out by a hand-operated valve 20 which is arranged near the point of 85 connection with the supply-pipe 15.

85 The pressure reducing valve, which forms an important feature of the invention and as illustrated in detail in Fig. 3, consists of a chamber 21 having connections at opposite 90 sides for the admission and discharge of the liquid, respectively, the latter being provided with an elbow or angular passage 22 which is covered with a strainer 22^a, and is downwardly directed at substantially the center 95 of the chamber. This passage is normally closed by a valve 23 under the influence of a spring 24, and has a depending stem which is guided within a plug 25 threaded through the bottom of the chamber.

100 The valve 23 is faced with a disk of leather or other soft material 26, which is clamped about its edges between the valve head and an internally threaded and flanged collar 27, the said collar being formed integrally with a 105 yoke 28 which straddles the inner end of the passage 22. The top of the chamber 21 is internally flanged and receives a screw-

threaded cap 29, between which and said flange is clamped a rubber or other like diaphragm 30, the latter being also connected at the center by binding it between the top 5 of the yoke and the flanged head of a stem 31, the connection between the yoke and the stem being effected by providing the former with a threaded stud, as clearly shown.

The cap 29 is internally threaded through 10 its center for receiving a thimble 32, between which and the head of the stem 31 is interposed a spring 33, which acts to resist the pressure of the liquid as it is introduced within the chamber, and which may have the tension 15 adjusted thereon by the thimble 32 to regulate the relative difference between the pressures introduced and discharged from the chamber 21.

In the operation of the invention after it 20 is connected with one or more casks of beer, ale, etc., the pressure of the liquid is registered on the gage 9 and passes into the regulating valve 8, opening the valve 23 and reacting against the diaphragm 30, which is of 25 much greater area, as it passes to the pressure gage 10, and thence into the tank. By adjusting the thimble 32 the relative difference between the pressures recorded on the gages 9 and 10 may be varied in any desired 30 amount and the liquid may be drawn from the tank through the discharge-pipe 15 with as little or as much foam as desired.

If there is an excess of gas within the tank 5 it may be released by opening the valve in 35 the vent-pipe 14 which is ordinarily located near the point at which the beverage is drawn.

I have found in practice that after a barrel 40 of ale has been exhausted through my improved pressure reducer, a considerable quantity of gas is left in the barrel, usually thirty or more pounds. It is convenient to use this gas for washing out the tank; this being done by filling the tank with water, as 45 by unscrewing the coupling 16. The pressure in the barrel is then admitted to the top of the tank through the by-pass 18, and the three-way valve 11 opened to let the water and gas escape through the cock 13.

50 The invention as shown and described while being the preferred practical embodiment of my improved pressure reducer may

be modified in numerous particulars falling within the scope of the annexed claims.

Having thus described my invention, I 55 claim as new and desire to secure by Letters Patent:

1. A pressure reducer for gaseous liquids, comprising a tank for storing, cooling and settling the liquid, a pipe leading from the 60 liquid supply to said tank, a pressure reducing valve located in the length of said pipe, three-way valves in the length of the supply pipe at each side of the reducing valve, pressure gages carried by said pipe at the opposite sides of the reducing valve, a discharge pipe leading from near the bottom of the tank and passing through the top thereof, a vent-pipe connecting with the top of the tank, a by-pass connecting one of said three- 65 way valves and the discharge pipe, and hand-operated valves located in said by-pass and the discharge pipe adjacent to said tank. 70

2. A pressure reducer for gaseous liquids, comprising a tank, a pipe leading from the 75 liquid supply to the lower portion of the tank, a pressure reducing valve located in the length of the pipe, a discharge pipe leading from the tank, and means for passing a liquid from the supply pipe at the rear of the 80 reducing valve through the discharge pipe into the tank, and drain it therefrom through the supply pipe in advance of said valve.

3. A pressure reducer for gaseous liquids, comprising a tank, a pipe leading from the 85 liquid supply to said tank, a pressure reducing valve located in the length of said pipe, three-way valves in the length of said pipe at each side of the reducing valve, a discharge pipe leading from the tank, and a by-pass 90 connecting one of said three-way valves with the discharge pipe, whereby a liquid for washing out the tank may be introduced thereinto through the supply pipe, one of said three-way valves, by-pass and discharge 95 pipe, and drained therefrom through the other of said three-way valves.

In testimony whereof I have signed my name to this specification in the presence of two subscribing witnesses.

HARRY ASHTON REED.
